UNITED STATES PATENT OFFICE.

WILLIAM H. SMYTHE, OF WINTHROP, MASSACHUSETTS, ASSIGNOR TO MARY B.
SMYTHE, OF WINTHROP, MASSACHUSETTS.

STATIONERY-CABINET.

1,391,082.

Specification of Letters Patent. Patented Sept. 20, 1921.

Application filed April 3, 1920. Serial No. 370,928.

To all whom it may concern:

Be it known that I, WILLIAM H. SMYTHE, a citizen of the United States, and resident of Winthrop, in the county of Suffolk and 5 State of Massachusetts, have invented certain new and useful improvements in Stationery-Cabinets, of which the following is a specification.

This invention relates to means for holding 10 writing paper and envelopes in such manner as to render the sheets and envelopes easily accessible one at a time.

It is well known that in such places as clubs and hotel writing rooms it is customary 15 to keep small supplies of stationery on the tables or desks for the use of members or guests, and it is a matter of common knowledge that many of the sheets and envelopes become rumpled or dusty and otherwise unclean, and many are blown or get 20 pushed off onto the floor. The result is a loss to the clubs or hotels through the waste of paper which, usually, has been printed at considerable expense.

25 The principal object of this invention is to provide a strong and durable cabinet for holding envelopes and writing paper in sanitary, smooth and clean condition, and from which the articles can be removed singly, 30 with ease, and without disturbing the succeeding articles.

Another object is to provide a device of 35 this character which is compact and attractive, and which may be fastened to a desk or wall, and which can be readily stocked with fresh supplies of stationery.

With these and other objects in view, the invention consists in the cabinet constructed and arranged substantially as hereinafter 40 described and claimed.

Of the accompanying drawings—

Figure 1 is a front elevation of a stationery cabinet embodying the features of my invention.

45 Fig. 2 represents a section on line 2—2 of Fig. 1.

Fig. 3 represents a section on line 3—3 of Fig. 2.

50 Figs. 4 and 5 represent sections, on a larger scale, taken on lines 4—4 and 5—5 respectively of Fig. 3.

The cabinet is made of any suitable sheet metal the various pieces of which are joined by brazing, or according to any other 55 method not necessary to illustrate in the

drawings, so as to provide an envelop receptacle 10 and a sheet receptacle 11 accessible to both of which is obtained by a cover 12 hinged at 13. The back plate 14, bottom or base 15 and side walls 16 of the cabinet as 60 a whole, are relatively positioned like portions of a rectangular box. The front however comprises an upper section 17, a lower section 18 of less height, and an intermediate upwardly and rearwardly curved section 19. A partition 20 between the receptacles 10 and 11 may be integral with the section 19.

The bottom 21 of receptacle 10 is cut away or formed with an opening 22 which preferably 70 has a shape substantially corresponding to the shape of the flap of an envelop.

The receptacle 11 is provided with a rear wall 23 curved to so correspond with the front section 19 as to provide a receptacle 75 of substantially uniform transverse area. The curvature of the front and rear walls of the receptacle 11 is such that substantially half or more of the height length of the sheets *c* therein will be curved forward toward the bottom of the receptacle.

Extending across the lower edge of the front section 19 is a narrow slit 24 which is recessed at the middle to provide a finger 85 opening 25.

The lower edge of the wall 23 is curved upwardly on a forward slant and terminates at the slit 24. This upwardly and forwardly inclined portion presents a sheet-deflecting surface 26 which serves partly to hold back 90 the package of sheets *c* and partly to turn or deflect their lower edges toward the delivery slit 24. The general curvature of the receptacle 11 as a whole, keeping all of the sheets *c* therein curved substantially from 95 bottom to top, coacts with the inclined portion 26 in preventing such free gravitation of the sheets as might cause the top sheets to successively slide out through slit 24, and yet a top sheet can readily be drawn out by 100 anyone who inserts a finger, or the rubber end of a pencil or other friction device, through the opening 25, and who then frictionally starts that sheet out.

To aid in preventing sheets other than 105 the top one from issuing I prefer to provide a spring friction retarder 27 which may consist of a block of rubber. The top of this retarder, as best shown by comparing Figs. 1 and 5, projects slightly above the plane 110

of the slit 24, and is in alinement with the recess 25, so that any top sheet having a tendency to slide freely out through slit 24 is arrested because its mid-width would have to be deflected out of alinement with the rest of its forward edge in order to pass the retarder. A finger or other friction member however, pressing down on the portion of the top which is on the retarder 27, 10 is easily able to draw the sheet out.

It will now be understood that the contents of the cabinet can be removed singly without the aid of any mechanical feeding device, and therefore there is nothing to get 15 out of order. Gravity alone insures an envelop and a sheet being accessible for manual removal.

A single cover (12) keeps both compartments closed against access of dust. Envelops are placed in compartment 10 in such 20 position that they will successively occupy the position indicated by dotted lines *a b* in Fig. 2, and the flap *b* of the lower one will drop sufficiently through opening 22 to enable that envelop to be drawn out.

The curved sections 19, 23, being rigidly connected with other sections 14, 15, 16 of the cabinet, impart strength to the whole as they constitute a truss-like portion connecting the top compartment with the base. 30

At the same time the curvature is not on an arc which will result in the paper sheets,

even when in the compartment for a long time, becoming so curled that they will not lay out flat for writing thereon.

35

Of course advertisements may be borne by any portion of the cabinet. The curved surface of member 19 however presents an especially desirable location for advertisements because a person applying a finger at 40 25 to remove a sheet of paper can hardly fail to notice matter immediately above and in line with his finger.

I do not limit myself to the specific details illustrated and described. For instance 45 I may employ more than one of the retarders 27.

Having now described my invention, I claim:—

In a device of the character described, a 50 compartment for paper sheets having a curved front wall and a correspondingly curved rear wall, the lower portion of the latter being inclined upwardly to a point closely adjacent the lower edge of the front 55 wall, a narrow slit being provided at said point, and a rubber retarder extending higher than the lower edge of the slit, said front wall having a recess above said retarder.

60

In testimony whereof I have affixed my signature.

WILLIAM H. SMYTHE.
